UNITED STATES PATENT OFFICE

ALFRED H. AVERY, OF MALDEN, MASSACHUSETTS, ASSIGNOR TO NORTH AMERICAN CHEMICAL COMPANY, OF CAMBRIDGE, MASSACHUSETTS, A CORPORATION OF MASSACHUSETTS

SHOE-FILLING MACHINE

Application filed February 20, 1931. Serial No. 517,237.

This invention relates to machines for spreading shoe bottom filler in the bottom cavities of shoes, and consists in certain improvements upon and modifications of the 5 shoe bottom filling machine described in my application for patent Serial No. 516,862, filed February 19, 1931.

Formerly shoe filler of the plastic, spreadable kind has been spread in the bottom cavities of shoes by hand. In laying bulk filler, which has been in general use for many years, the operator would dip or scoop a quantity of filler, suitable for a single shoe cavity, by means of a hot spreading knife 10 or spatula out of a larger mass or bulk of filler, usually previously softened and conditioned for spreading. He would then deposit the segregated quantity of filler in the shoe bottom cavity and spread it by means 15 of the spatula within the cavity in much the same manner as a mason lays and spreads mortar; and finally he would usually pass a hot roller back and forth over the spread layer to compress and smooth it. In laying 20 individual, leaf-like pieces of plastic filler material, which have recently come on the market, he would follow a similar procedure, spreading the pre-conditioned filler piece with the spatula and/or with a roller. 25 This handwork was extremely laborious owing to the nature of the filler material and was in many ways unsatisfactory; and it is the object of the present invention to provide a machine for more efficiently and 30 expeditiously filling shoes, for spreading the filler more completely throughout the cavity, making a more uniform filler layer and compacting and compressing the layer more firmly, for simultaneously flattening the welt seam and leveling the welt 35 and the entire shoe bottom, and generally producing filled shoes superior to those produced by previous methods.

Important novel features of the present 40 invention consist in the vibrating pressing and spreading member; and in the automatic starting and stopping of the press operating mechanism by the insertion and removal of the shoe being operated upon. These 45 and other features will be herein more fully

described and particularly pointed out in the claims.

In the accompanying drawings,

Fig. 1 is a side elevation of a shoe bottom filling machine embodying the invention; 55

Fig. 2 is a plan view of the machine;

Fig. 3 is a partial section on line 3-3 of Fig. 2;

Fig. 4 is a partial section on line 4-4 of Fig. 1; 60

Fig. 5 is a plan view of the heated shelf for holding a supply of shoe filler; and

Fig. 6 is a section on line 6-6 of Fig. 5.

As the present invention has certain features in common with that shown in my 65 said application for patent Serial No. 516,862, the same reference numerals, so far as applicable, will be used for convenience as in said former application.

The machine comprises a frame 1 provided at its front side with a bearing within which is rotatably mounted the vertical stem or spindle 68 of a head 69, which serves as a rigid backing or support, as well as a carrier, for a heated pressing and spreading member indicated generally at 20. The 70 pressing and spreading member is a flexible, slightly bowed pad constructed as more fully described in my said application Serial No. 516,862. 80

To the upper end of the stem or spindle 68 is fixed the hub of a laterally extending arm 70, connected by a pitman 71 with an eccentric 72, fast on a transverse shaft 73, 85 on which is also fixed a worm gear 74.

Worm gear 74 is continuously driven by a worm 75, (Fig. 2) fast on the armature shaft of an electric motor M, fixed in position upon the top of the frame 1.

Through the mechanism just described 90 the pad 20 is continuously oscillated or vibrated on a vertical axis while the machine is in use, thereby imparting to the working face of the pad 20 a vibration of partial rotation in a plane transverse to the direction 95 of pressure. This materially assists in the proper spreading, distribution and leveling of the filler material while the shoe is held pressed against the pad 20, as hereinafter described. 100

During the operation of spreading the filler material in the bottom cavity of a shoe, the shoe is moved upwardly by the shoe support so that the bottom of its forepart and the bottom of its welt are forcibly pressed against the bottom plate 58 of the hot pressing and spreading pad 20, as shown in Fig. 1. The filler material which has been deposited in the bottom cavity of said forepart is thereby spread and leveled and at the same time the filler is subjected to heat treatment by the hot pad.

- The shoe support comprises a swinging frame or body member 76, which is pivotally supported by a cross-rod 77 fixed at its ends to the machine frame 1. The swinging frame 76 is provided with an arm 78 to which the forward end of a connecting rod 79 is pivotally connected. At its rear end the connecting rod 79 is provided with a slideway 80, within which is slidably mounted a block 81. Block 81 is carried upon a crank 82 forming part of an intermittently operated shaft 83. A spring 84 disposed between the block 81 and an adjustable abutment screw 85 at the rear end of the slideway 80 yieldingly opposes rearward movement of the block 81 relatively to the connecting rod 79.
- Loosely mounted on the shaft 83 is a gear 86 (Figs. 1, 2 and 4) which is continuously driven by a pinion 87 fast on the shaft 73. This gear 86 has one side made as a clutch member 86^a to cooperate with a complementary clutch member 88 (Fig. 4) splined to, but movable axially on, the shaft 83. A spring 89 yieldingly urges the clutch member 88 toward the clutch member 86^a of the gear 86.
- The clutch member 88 is provided with a radially projecting stud or roll 90 to cooperate with a shipper member 91, which is pivotally mounted at 92 on the frame of the machine.
- When the shipper member 91 is held in its retracted and inoperative position, illustrated in Figs. 1 and 4, the spring 89 holds the clutch member 88 in engagement with the clutch 86^a on gear 86 so that the crank 82 of shaft 83 operates through the connecting rod 79 to rock or reciprocate the swinging frame 76 on the cross-rod 77. When the shipper member 91 is permitted to swing from the position indicated by dotted lines in Fig. 1 into its operative position where it is close to or rests against the periphery of the clutch member 88, while the latter is rotating in the direction indicated by the arrow in Fig. 1, the roll or stud 90 on said clutch member will ride up on to the cam portion 91^a of shipper member 91 and come to rest against a stop shoulder 91^b on the shipper member, thereby disengaging the clutch member 88 from the clutch gear 86 and stopping further os-

cillation of the body member 76. The stud or roll 90 thus engages the stop shoulder 91^b at a moment when the connecting rod 79 is at the limit of its movement in the direction of the swinging frame 76.

It will also be clear that when the shipper member 91 is moved to its inoperative position against a stop screw 93, the spring 89 will return the clutch member 88 into engagement with the clutch gear 86 and the operation of the body member 76 will be resumed and continue until the shipper member 91 is again returned to its operative position.

Supported by and fixed upon swinging frame 76 are two spindles 94 (Figs. 1 and 4) to the lower end of each of which is secured an arm 95. These two arms embrace a block 96, which is provided at its opposite sides with trunnions 97, immovably clamped within bearings provided on the arms 95 by means of cap plates 98 and screws 99.

The block 96 is made with a central threaded hole to receive the threaded stem 100 of a toe rest 101, which is provided at its upper end with a crotch to support the forepart of a shoe S, as shown in Fig. 1. This crotch is preferably covered with a layer of cushioning material such as rubber. Upon the threaded stem 100 is mounted a hand-wheel nut 102 by means of which the stem is locked in adjusted position. By loosening the nut-wheel 102 and rotating the stem 100 the latter may be adjusted vertically as required by the shoe being operated upon. Also, the cap plates 98 and screws 99 provide for adjusting the stem 100 angularly on the trunnions 97 as may be required to fit the shoe support to the shoe that is being operated upon.

Each spindle 94 pivotally supports an outwardly extending arm 40. The two arms are yieldingly urged toward each other by means of a spring 41 connecting the same. Pivotally mounted at 46 upon the top side of each arm 40, adjacent the outer end thereof, is a welt supporting member 45. The two welt supporting members have their inner ends connected by a spring 47 which yieldingly urges said arms toward each other.

Each member 45 is a metal plate formed adjacent its inner end with an arcuate slot 48, concentric with the pivot 46, to receive a screw 49^a carried by arm 40. This screw serves to hold the laterally movable end of the plate 45 against the top of its arm without interfering with the movements of the plate on its pivot 46 under the influence of spring 47 or of the shoe.

The inner edge of each welt supporting plate 45 is beveled or undercut so as to enable the same to fit closely into the seam crease between the welt and the upper of the shoe; and the welt engaging edge of

each plate is also curved as indicated by dotted lines at 103 in Fig. 4, so as to approximate the longitudinal contour of the shoe.

5 Pivottally mounted on the swinging frame 76 between the arms 40 is a lever or trip 104, which extends upwardly to cooperate with the toe of the shoe S. The lever 104 also carries a tailpiece 104^a which extends 10 downwardly to cooperate with a roll 105 carried by an arm 106 fast on a rock shaft 107. This rock shaft 107 has fast on it another arm 108 connected by a link 109 with the shipper member 91.

15 When there is no shoe upon the shoe support the weight of the shipper member 91, assisted if desired by a spring, holds said shipper member at the limit of its movement toward the clutch member 88 with the upper 20 arm of lever 104 inclined forwardly into the path of the shoe, as shown by dotted lines in Fig. 3. With the parts in these positions, the shoe support is at rest because of the engagement of the shipper member 91 25 with the stud or roll 90 of clutch member 88.

When a shoe, upon the forepart of which a quantity of filler material has been deposited, is slid endwise and toe first into position between the arms 40, while the shoe 30 support occupies the position shown in Fig. 3, the shoe acts through the trip lever 104, tailpiece 104^a, stud or roll 105, arm 106, rock shaft 107, arm 108 and link 109 to retract shipper member 91, whereupon the clutch 35 88 is thrown in and the operation of the shoe support is automatically started. When the shoe S is fully in position upon the shoe support, the curved portion of the tailpiece 104^a of lever 104, which is in engagement 40 with the roll 105, is approximately concentric with the axis of pivot rod 77, so that the reciprocating movements imparted to the shoe support do not disturb the position of the shipper member 91.

45 It will be understood of course that when the shoe is shoved into position on the shoe support as described, the beveled inner edges of the plates 45 are pressed by the spring 47 closely into the seam crease of the shoe 50 so that substantially the entire overhanging welt rests upon and is supported by said plates when the shoe is forcibly pressed against the pad 20. In this way, not only is the filler material spread, leveled, distributed and evened with respect to the 55 upstanding welt seam, but the component layers of the welt seam are crushed down, compressed and evened, and the welt itself is leveled and evened substantially to the 60 plane of the rest of the shoe bottom.

It is also a feature of the above described construction that the engagement of the welt seam with the bottom plate 58 of the pad 20 prevents the filler material from 65 spreading outwardly on to the welt and

compels any surplus material to be displaced or extruded rearwardly on the shank of the shoe, after the forepart has been filled to its capacity. Such surplus material may readily be knocked or scraped off. 70

The machine is provided at one side with a shelf 110, which is furnished upon its under side with heating units 111 and 112 serving to heat the shelf, and particularly the front marginal part thereof, and the 75 supply of filler material resting thereon. The heating unit 111 extends across the shelf 110 for nearly its full width, while the unit 112 is relatively shorter and positioned immediately adjacent the outer side of the 80 shelf. The heating units are disposed within pockets provided upon the under side of the shelf and are held within said pockets by means of a sheet metal plate 113 fastened by screws to the shelf. 85

Beneath the shorter unit 112 is arranged a supplemental sheet metal plate 114, forming a knife heater and holder. The plate 114 is yieldingly supported by means of springs 115 resting at their lower ends 90 against the heads of screws 116 extending downwardly from shelf 110 loosely through apertures provided in plate 114. The front marginal portions of the two plates 113 and 114 are flared apart to provide an 95 entrance for the edgewise insertion of the blade of the knife or spatula.

The filler material, which lies in bulk on the heated shelf 110, is transferred to the shoe S, before the latter is placed upon the 100 shoe support, by means of a knife or spatula previously heated in the spring pressed holder 114. In practice two or more knives are provided and one is heating while the other is being used. 105

In operation, after a measured quantity of filler, or it may be a piece of filler if the 110 filler is used in piece form, has been deposited in the bottom cavity of the shoe to be filled, the shoe, still on its last, is shoved into position between the welt supporting plates 45, 45, with its welt resting on the welt supporting plates and the forepart of the shoe resting on the toe rest 101. When the shoe is pushed fully into position on the 115 supports the toe of the shoe will actuate the trip 104, thereby withdrawing the shipper 91, throwing in the clutch and starting the operation of the swinging frame 76. The frame 76 and the shoe supports carried thereby will force the shoe bottom, with its unspread filler, into pressing and spreading engagement with the pad 20, thus spreading, leveling, distributing and compacting the filler throughout the shoe bottom cavity, and at the same time flattening and compressing the welt seam, and evening, leveling and smoothing the entire shoe bottom including the filler layer, the welt seam and the welt, as described in my said appli- 120 125 130

cation Serial No. 516,862. In the presenting or spreading member and the shoe support toward and from each other, and
machine however these functions are materially aided by the back and forth partial rotation or vibration of the pad 20 in the
5 plane of the filler layer transverse to the direction of pressure, which supplements the spreading, distributing and compressing action of the direct vertical pressure between the pad 20 and the shoe supports.
10 When the swinging frame 76 descends after the spreading operation, the operator pulls the shoe out from its supports, thereby releasing trip 104, which permits the shipper 91 to throw out the clutch 88 and so brings
15 the swinging frame to rest in open position ready to receive another shoe upon the shoe supports.

I claim:

20 1. A shoe bottom filling machine comprising a pressing and spreading member, a shoe support, means to impart relative movement between the pressing and spreading member and the shoe support toward and from each other, and means to vibrate the pressing and spreading member in a plane transverse to the direction of pressure during its operation on the shoe bottom.

30 2. A shoe bottom filling machine comprising a pressing and spreading member, a shoe support, means to impart relative movement between the pressing and spreading member and the shoe support toward and from each other, and means to impart to the pressing and spreading member a vibration of rotation in a plane transverse to the direction of pressure during its operation on the shoe bottom.

40 3. A shoe bottom filling machine comprising a pressing and spreading member, a shoe support, means to impart relative movement between the pressing and spreading member and the shoe support toward and from each other, and means to impart to the pressing and spreading member a vibration of partial rotation on an axis substantially parallel to the direction of pressure, thereby to vibrate the working face of said member in a plane transverse to the direction of pressure during its operation on the shoe bottom.

50 4. A shoe bottom filling machine comprising a pressing and spreading member, a shoe support, means to impart relative movement between the pressing and spreading member and the shoe support toward and from each other, a spindle, to which the pressing and spreading member is attached, mounted on the machine frame on an axis substantially parallel to the direction of pressure, and means to impart to said spindle a vibration of partial rotation.

60 5. A shoe bottom filling machine comprising a pressing and spreading member, a shoe support, operating mechanism to im-
65 part relative movement between the press-

port toward and from each other, and mechanism controlled by a shoe when placed in position upon and when removed from said shoe support for starting and stopping said operating mechanism.

70 6. A shoe bottom filling machine comprising a pressing and spreading member, a shoe support, operating mechanism to impart relative movement between the pressing and spreading member and the shoe support toward and from each other, mechanism for starting and stopping said operating mechanism, and a trip in the path of and actuated by a shoe when placed in position upon and when removed from said shoe support for controlling the starting and stopping mechanism.

75 7. A shoe bottom filling machine comprising a pressing and spreading member, a shoe support, operating mechanism to impart relative movement between the pressing and spreading member and the shoe support toward and from each other, mechanism for starting and stopping said operating mechanism, a trip in the path of and actuated by a shoe when placed in position upon and when removed from said shoe support for controlling the starting and stopping mechanism, and connections between the trip and the starting and stopping mechanism so organized and arranged that while the trip is engaged by a shoe in position on the shoe support, the starting and stopping mechanism will be held in position to permit the operating mechanism to continue to operate notwithstanding the relative movement between the shoe support and the pressing and spreading member.

80 8. A shoe bottom filling machine comprising a pressing and spreading member, a swinging frame journaled on the frame of the machine, a shoe support carried by the swinging frame, operating mechanism to move the swinging frame and shoe support toward and from the pressing and spreading member, mechanism for starting and stopping the operating mechanism, a trip carried by the swinging frame and located in the path of and actuated by a shoe when placed in position upon and when removed from said shoe support for controlling the starting and stopping mechanism, and connections between the trip and the starting and stopping mechanism adapted in all positions of the swinging frame, while the trip is engaged by a shoe in position on the shoe support, to hold the starting and stopping mechanism in position to permit the operating mechanism to continue to operate.

85 9. A shoe bottom filling machine comprising a pressing and spreading member, a pair of welt supporting members adapted to engage underneath the welt of a shoe along

80

85

90

95

100

105

110

the seam crease between the welt and the upper, operating mechanism to impart relative movement between the pressing and spreading member and the welt supporting members toward and from each other, mechanism for starting and stopping said operating mechanism, and a trip located between the welt supporting members adapted to be actuated by the toe of a shoe when inserted between and when removed from said welt supporting members for controlling the starting and stopping mechanism.

10. A shoe bottom filling machine comprising a pressing and spreading member, a pair of welt supporting members adapted to engage underneath the welt of a shoe along the seam crease between the welt and the upper, a toe rest between and below the welt supporting members adapted to support the forepart of the shoe, operating mechanism to impart relative movement between the pressing and spreading member and the shoe supporting members toward and from each other, mechanism for starting and stopping said operating mechanism, and a trip located behind the toe rest and between the welt supporting members adapted to be actuated by the toe of a shoe when inserted between and when removed from said welt supporting members for controlling the starting and stopping mechanism.

11. In a machine for operating on a shoe, a shoe support, and an adjustable mounting therefor comprising a frame, a block journaled on a horizontal axis on the frame, and a stem vertically adjustable on the block and carrying a shoe rest at its upper end, whereby the shoe rest and stem may be adjusted both angularly and vertically.

12. A shoe bottom filling machine comprising a pressing and spreading member, a shoe support, means to impart relative movement between the pressing and spreading member and the shoe support toward and from each other, and means to impart relative movement between the pressing and spreading member and the shoe support in a plane transverse to the direction of pressure during the operation of said member on the shoe bottom.

Signed by me at Boston, Massachusetts this seventeenth day of February, 1931.

ALFRED H. AVERY.
